CLAIM

The ornamental design for an ultrasound catheter as shown and described.

DESCRIPTION

FIG. 1 is a perspective view of the ultrasound catheter;

FIG. 2 is a front elevational view thereof;

FIG. 3 is a rear elevational view thereof;

FIG. 4 is a top plan view thereof;

FIG. 5 is a bottom plan view thereof;

FIG. 6 is a left-side elevational view thereof;

FIG. 7 is a right-side elevational view thereof;

FIG. 8 is a detail view of area “8” shown in FIG. 2;

FIG. 9 is a detail view of area “9” shown in FIG. 3;

FIG. 10 is a detail view of area “10” shown in FIG. 4; and,

FIG. 11 is a detail view of area “11” shown in FIG. 5.

The evenly spaced broken lines depict unclaimed parts of the ultrasound catheter and form no part of the claimed design. The dot-dash chain lines depict a boundary of the claimed subject matter and form no part of the claimed design. The dot-dot-dash chain lines forming rectangular shaped boxes around certain portions of FIGS. 2 to 5 depict areas shown as detail views in FIGS. 8 to 11, and form no part of the claimed design.
